UNITED STATES PATENT OFFICE.

GEORGE F. PIERCE, OF CHICAGO, ILLINOIS.

SYSTEM OF SUPPLYING HYDROGEN GAS TO FURNACES.

1,172,551.

Specification of Letters Patent. Patented Feb. 22, 1916.

Application filed April 29, 1914. Serial No. 835,166.

To all whom it may concern:

Be it known that I, GEORGE F. PIERCE, a citizen of the United States, residing at Chicago, in the State of Illinois, have invented 5 certain new and useful Improvements in Systems of Supplying Hydrogen Gas to Furnaces, of which the following is a specification.

My invention relates to a system of supplying hydrogen to furnaces, and the objects 10 of the invention are to obviate grate-clogging from lignite, or bituminous coal; to enhance combustion of fuel and gases arising therefrom; and to combat smoke generation, 15 especially when the furnace doors are open to charge the furnace with fuel.

In effecting the above-mentioned objects I 20 employ hydrogen combined with oxygen both in liquid form as water, or gaseous form as steam or vapor. The entire steam supply may be taken from the furnace boiler, but in order to economize the boiler steam, I provide independent steam generating apparatus to supplement the boiler 25 steam. The boiler steam supply and the independent steam supply are interconnected, so that both supplies may be used either simultaneously or independently.

The system is applicable to furnaces employed 30 for either domestic or commercial purposes, or for high pressure or low pressure steam plants.

In order that the invention may be fully understood, reference will now be made to 35 the accompanying drawings, in which:

Figure 1 is a diagrammatic view of my system with the steam boiler to which it is connected removed. Fig. 2 is a vertical longitudinal section of a furnace and a boiler 40 provided with my system, said boiler being in elevation. Fig. 3 is a vertical longitudinal section of a spray nozzle employed in carrying out the invention. Fig. 4 is a horizontal section of a plurality of tubes with 45 steam jets arranged therein.

1 designates a bridge-wall, 2 an ash-pit, and 3 a grate similar in construction to the grate disclosed in my copending application filed July 14, 1913, Serial No. 778,924.

50 4 designates a steam boiler arranged above the grate 3, which latter is supported upon an endless perforate pipe 5 consisting of straight lengths connected by four-way couplings 6. The pipe 5 constitutes a rectangular vaporizer, or steam generator, for a purpose which will hereinafter appear. Dead-

heads 7 project laterally from the unions 6 to be embedded in the side walls 8 of the furnace, to firmly support the pipe 5 and the parts connected thereto. The pipe 5 skirts 60 the ash-pit walls to be out of the way of ashes falling through the grate, so that the perforations in said pipe will not become clogged.

By means of the unions 6 the perforate pipe 65 5 is connected with the three-way couplings of an underlying endless pipe 9, which is imperforate. One of the unions 6 communicates with the underlying pipe 9 through the intermediacy of a header 10, connected to a 70 steam supply pipe 11 and a water supply pipe 12. The lower end of the header 10 is provided with a drain-cock 10^a, through which the pipes 5 and 9 may be emptied when desired. The steam supply pipe 11, 75 communicates at its lower end with two nozzles 13 (Fig. 4), one of which projects into one of the longitudinal lengths and the other into one of the transverse lengths of pipe 9, to supply the same with steam in lieu of 80 water when desired.

The steam pipe 11 is provided with a valve 14 and communicates at its upper end with a steam pipe 15, communicating with the steam chamber 16 of a spray nozzle 17, consisting of said steam chamber 16 and a water chamber 18. The water chamber 18 is provided adjacent the steam chamber 16 with 85 perforations 19 for the discharge of water, which is thrown in a fine fan-shaped spray 90 over the fuel in the furnace by steam issuing through perforations 20 in the steam chamber 16.

The water chamber 18, of the spray nozzle 17, is supplied with hot water from a coil 95 21, arranged in the upper portion of the furnace and communicating at its upper end with a tank 22, a check-valve 23 being provided to prevent back pressure in the coil 21 from blowing into said tank 22. Tank 22 100 is supplied with water through a pipe 24 leading from any suitable source, the discharge of water through said pipe 24 being controlled by a valve 25, provided with a float 26, which drops and opens the valve 105 when the water level in the tank falls below a certain point. In order to prevent the water in the tank 22 from freezing in cold weather, I provide a pipe 27 for conducting steam thereto, said pipe communicating with 110 a main steam supply pipe 28 leading from the boiler 4. The pipe 27 is provided with

a valve 29 for cutting off steam to the tank 22 when not required.

Returning to the water supply pipe 12, the intake end thereof communicates with a container 30, arranged approximately on a level with the pipes 5 and 9. A check valve 31 is placed on the pipe 12 to check any back pressure from the pipes 5 and 9. As shown in Fig. 1, I may use a single container 30 for each pair of furnaces, a pair of pipes 12, with their valves 31, being shown as connected to the container. The container 30 is supplied with water from the tank 22 through a pipe 32, provided with a valve 33 for checking or regulating the flow of water through said pipe. The discharge end of pipe 32 is provided with a valve 34, having a float 35 which opens when the level of the water in the container falls below a certain point, the object being to maintain said level on a line just below the perforations in the pipe 5. By having the water from the container 30 enter the pipe 9 before entering the perforate pipe 5, said water is heated and readily converted into vapor or steam, which, on intermixing with the oxygen in the furnace, forms a highly combustible gas, that ignites and produces an intense heat, thereby consuming the carbon and gases arising from the products of combustion, which usually escape through the stack. Thus the greatest efficiency and economy in the consumption of fuel is obtained by the use of my system.

In order to prevent the grate 3 from becoming unduly heated and the consequent lodgment thereon and clogging thereof by sulfur and other products of combustion detrimental to said grate, I arrange for a supply of vapor in the ash-pit by introducing water therein through a pipe 36, communicating with a small container 37, supplied with water through a branch pipe 38 leading from the pipe 32. The water in the ash-pit 2 is maintained at substantially the same level as the water in the small container 37, through the intermediacy of a float-controlled valve 39, arranged to open the lower end of the branch pipe 38 when the water falls below a predetermined level in said container 37.

Steam is supplied to the furnace above the grate 3, through the intermediacy of nozzles 40, arranged on opposite sides of the spraying nozzle 17 and supplied with steam through a pipe 41, communicating with a manifold 42, communicating with the main supply pipe 28 and two bypasses 43 leading from said main supply pipe 28 and provided at opposite sides of the latter with valves 44. The manifold 42 is provided at points between its connections with the main supply pipe 28 and the pipes 43 with quick opening valves 45, for a purpose which will hereinafter appear. As disclosed by the

diagram, Fig. 1, the manifold 42 and its connections are in duplicate for supplying two furnaces, only one of which, however, is shown. The two furnaces may be supplied either simultaneously or independently by proper manipulation of the valves 44 and 45. When the plant contains but one furnace, the pipe connections of the manifold at one side of the main supply pipe 28 are dispensed with. When the plant contains two furnaces, each is supplied with a spray nozzle 17, nozzles 40, and a small container 37.

In order to increase the draft in the stack A when charging the furnace, I lead a steam jet 46 thereto from a pipe 47, communicating with the manifold 42 adjacent the bypasses 43. Pipe 47 is provided with check valves 48 to prevent steam from flowing through said pipe to opposite sides of the manifold 42 when only one of the furnaces is in operation.

49 designates a reducing valve to regulate the pressure of the steam flow through the main supply pipe 28, which communicates with a bypass 50 for low pressure steam when the latter is to be employed instead of high pressure steam. The pipes 28 and 50 are provided with valves 51 and 52, respectively, to control the flow of steam therethrough.

53 designates a perforate ring arranged below the central pyramidal portion 3^a of the grate, to discharge steam thereunder to prevent the same from burning out and to prevent the lodgment of sulfur and other deleterious products of combustion thereon. The ring 53 communicates with a pipe 54 leading from the pipe 15 and in which is provided a valve 55.

In practice, the valves 44, either one or both as the case may be, are normally left slightly open to supply the nozzles 17 and 40 with a small quantity of steam when the furnace doors are closed, but when the furnace doors are open for the purpose of charging the furnace, a stronger flow of steam is desired to intermingle with the carbon in the smoke and precipitate it into the fire for consumption, so that the quick opening valves 45 are opened to admit the necessary additional steam. The steam that arises from the water in the ash-pit passes directly through the interstices in the grate and largely prevents grate clogging from sulfur deposits, which occur when bituminous coal is burned. The steam issuing from the perforate pipe 5 passes upward through the grate and mingles with the products of combustion, the effect being to raise the temperature of the flame and more thoroughly consume not only the fuel but the products of combustion as well, which in ordinary furnaces are ejected from the stack as smoke. A valved pipe 56, com-

municating with the pipe 28, is provided for connection to a flue-blower, or cleaner, when desired.

Having thus described my invention, 5 what I claim and desire to secure by Letters Patent, is:

1. The combination with the grate of a furnace, of a vaporizer supported adjacent the under side of the grate, a pipe arranged 10 beneath the vaporizer in coincidence therewith and connected thereto for communication, means for supplying water to the pipe, and automatic means for controlling the admittance of the liquid to the pipe to maintain the water therein at a predetermined 15 level.
2. The combination with a furnace having a fire box and a grate in the latter, of a vaporizer comprising a perforated piping 20 disposed beneath the grate in proximity to the underside and outer edge thereof, a series of spaced couplings depending from the perforated piping, a water supply pipe supported by the couplings in coincidence 25 with the perforated piping, laterally extending dead heads secured to the couplings to support the vaporizer from the furnace wall, and means for replenishing the supply of water in the supply pipe.
3. In combination with a steam boiler, of a steam pipe communicating therewith, spaced steam pipes, nozzles connected with the latter and adapted to be arranged within 25 a furnace structure, a manifold communicatively connecting the first steam pipe with the spaced steam pipes, a quick-opening

valve in the manifold on each side of the connection with the first steam pipe, by passes leading from the latter to the manifold at points beyond the quick-opening 40 valves, valves in the by passes, a U-shaped pipe communicating with the manifold at points beyond the by pass connections, and a jet leading from the U-shaped pipe for disposal in the stack of the furnace to provide a forced draft.

4. In combination with a steam boiler, of a steam pipe communicating therewith, spaced steam pipes, nozzles connected with the latter and adapted to be arranged within 50 a furnace structure, a manifold communicatively connecting the first steam pipe with the spaced steam pipes, a quick-opening valve in the manifold on each side of the connection with the first steam pipe, by 55 passes leading from the latter to the manifold at points beyond the quick-opening valves, valves in the by passes, a U-shaped pipe communicating with the manifold at points beyond the by pass connections, check 60 valves arranged in the U-shaped pipe for opening toward each other, and a jet leading from the U-shaped pipe between the check valves for disposal in the stack of the furnace to provide a forced draft.

In testimony whereof I affix my signature, in the presence of two witnesses.

GEORGE F. PIERCE.
